NURSING BOTTLE HOLDER

Herbert Hyams, Baldwin, N. Y.

Application September 29, 1943, Serial No. 504,202

4 Claims. (Cl. 248—106)

This invention relates to nursing bottle holders of the character employed for supporting a nursing bottle while an infant is being fed. Nursing bottle holders are usually constructed in various ways. Some of them are arranged to be attached to parts of the crib and to adjustably hold a bottle in various positions to enable the child to be fed therefrom. Other devices are in the form of pads or similar supports which are placed on the crib close to the child and on which are bottle is propped or otherwise held to make it available to the child.

The primary objection to the first type of bottle holder is that it requires attachment to and detachment from parts of the crib, and it also usually has projecting parts likely to contact with and injure the child. Any holders requiring precise adjustment of parts to position the bottle suitably, are invariably discarded because of the trouble involved in using them. An objection found in many of the types in the second group is the difficulty in holding the bottle at the proper inclined or tilted position to enable the contents to be steadily withdrawn by the feeding child.

The present invention belongs in the second class of device, in that it constitutes a support which is placed on the crib close to the child and it holds the bottle available to the child. An object of the invention is to provide, in a device of this character, means by which the bottle may be tilted to enable the milk to be readily withdrawn, and by which the degree of tilt or inclination of the bottle may be readily increased as the milk is consumed.

Another object of the invention is to provide means by which the elevation of the nipple on the bottle from the surface of the bed can be maintained as the degree of tilt of the bottle increases.

Still another object of the invention is to provide a simple, easily operated bottle holder which will hold the bottle at the proper position to enable the child to easily receive the milk therefrom; which can be readily adjusted as the milk is consumed so that the child can be comfortably fed with a minimum of effort on the part of the mother or nurse.

In the accompanying drawing forming a part hereof, and in which an illustrative embodiment of the invention is shown, Fig. 1 is a vertical sectional view through a nursing bottle holder constructed in accordance with the invention; Fig. 2 is a plan view of the same, with a part in section to disclose construction; Fig. 3 is a rear elevation of the holder, and Fig. 4 is a front view of the same, with a part in section.

The device may be made of any suitable material such as wood, metal, fibre board or other sheet material, and it is provided with a flat base member 1 on which it rests. The base member is preferably of substantial size, relative to the height of the holder, to thereby provide stability to the device. The bottom face of the base member 1 is preferably provided with a non-slip surfacing 2, such as felt or the like. Rising from the opposite side edges of the base 1 is a pair of vertically disposed side walls 3 and 4 which constitute supports and act to support an adjustable tray or bottle-holding cradle 5.

The cradle 5, on which the nursing bottle 15 is supported in the manner indicated in dotted lines in Fig. 1, consists of a substantially channel-shaped member, having a bottom 5a, spaced side walls 7, and a curved front piece 6. The size and shape of the cradle 5 is such as to enable a nursing bottle 15 to be placed flatwise upon it, and it will snugly embrace the bottle, permitting the front end of the bottle and the nipple 20 thereon, to project sufficiently beyond the forward end 6 of the cradle to enable the infant to easily engage the nipple with his mouth. To securely hold the bottle in this position, an encircling strap or band 16 may be provided, as shown in Figs. 1 and 4 (the band being omitted from Fig. 3). Said strap or band 16, which extends across the bottle, may be permanently attached at one end, as indicated at 17, to the top of one of the side walls 7 of the cradle. The strap may be provided at its other end with a fastening element 18 for engagement with a complementary element located on top of the other side wall 7.

Extending laterally from the opposite sides of the cradle 5 near its forward end, is a pair of pins or studs 8, which are located in vertically disposed grooves 9 provided in the inside faces 40 of the side walls 3 and 4 of the holder. These pins 8 allow pivotal movement of the cradle within the grooves as well as vertical movement therein.

The base 1 is provided with a centrally located, longitudinally extending, groove 10 constituting a guideway for a cradle-adjusting member 11. Said member 11 causes raising and lowering movement of the cradle and it is manually slideable in the groove 10 and is provided on its upper edge with a cam surface 14 which engages the underface of the bottom 5a of the cradle. Thus, when the adjusting member 11 is engaged by the finger piece 12 and is manually slid along in the groove 10 toward the left, as viewed in Fig. 1, the surface 14 will tilt or incline the cradle 5.

to any desired degree to accordingly hold the bottle 15 in the desired tilted position. During this tilting movement of the cradle, the same will pivot about the pivot pins 8.

At its forward end, the adjusting member 11 is formed with a rounded nose 13 constituting an elevating means for the cradle. That is to say, when the adjusting member 11 has been moved to such an extent as to tilt the cradle and bottle supported by it to a considerable extent, the surface 13 will come into contact with the underface of the cradle bottom 5a and it will bodily elevate the cradle, the pins 8 at this time moving upwardly in the grooves 9.

Through this arrangement, the forward end of the cradle, and consequently the nipple end of the bottle held thereby, is prevented from being lowered to such an extent as to cause it to be difficult of access by the feeding infant. Thus, while the bottle is tilted as required, it is also automatically elevated when a predetermined degree of tilt of the bottle is reached.

From the foregoing, the operation of the device will be readily understood. It is placed upon the crib in such a position that the nipple will reach the child's mouth, the bottle being at first only slightly tilted. As the contents of the bottle are consumed, the mother or nurse will from time to time, increase the extent of tilt of the bottle by sliding the adjusting member 11 to the left, to thus tilt the cradle and bottle upwardly in progressive fashion. As the adjusting member 11 continues to be pushed to the left, the surface 13 thereon will be finally brought into contact with the bottom of the cradle, thus raising the cradle bodily upward, to thereby keep the nipple end of the bottle sufficiently elevated from the surface of the bed to enable the nipple to be conveniently accessible to the infant. By means of this arrangement, the desired tilt of the bottle, as well as the height of the nipple from the bed, can always be maintained so that the child can be fed with only occasional attention from the mother.

The device is such that it can be made in various attractive and ornamental forms and of numerous materials. Hence the embodiment shown is necessarily an illustrative one, the invention contemplating numerous modifications within the scope of the claims appended hereto.

What I claim is:

1. A nursing bottle holder comprising, a base, spaced side members arising from said base, a bottle-holding cradle pivotally mounted between the side members and capable of bodily rising movement between said side members, a slideable adjusting member movable along the base between the side members, said adjusting member having an inclined upper face operative against the under face of the cradle to thereby pivotally incline the cradle, said adjusting member also having a surface operative against the under side of the cradle to bodily raise the cradle and the bottle held thereby when a predetermined angle of tilt has been reached by the cradle.

2. A nursing bottle holder comprising, a base, spaced side members arising from said base, a cradle located between the side members, said cradle having laterally extending pivot pins located near its forward end, the side members having vertical grooves in which the pins are pivotal and are also vertically movable, and an adjusting slide movable beneath the cradle for both pivotally adjusting the cradle and also for elevating it vertically in said grooves.

3. A nursing bottle holder comprising, a base, spaced side members arising from said base, a cradle located between the side members, said cradle having laterally extending pivot pins located near its forward end, the side members having vertical grooves in which the pins are pivotal and are also vertically movable, a groove formed in the base between the side members, an adjusting slide manually movable in said groove, said slide having an upper surface operative against the under side of the cradle to tilt the cradle to a desired angle, said slide also having a lifting surface for bodily elevating the cradle and the bottle held thereby when a predetermined angle of inclination of the cradle is reached.

4. A nursing bottle holder comprising, a support, a pivoted bottle-holding cradle thereon, and a slide on the support having cam means for increasing the angle of the cradle when the slide is manually moved, and having means for bodily raising the cradle when a predetermined angle or tilt of the cradle is reached.

HERBERT HYAMS.
